UNITED STATES PATENT OFFICE

FREDRIK LJUNGSTROM, OF LIDINGO, SWEDEN

DESIGN FOR AN ELECTRIC FAN

Application filed June 1, 1931, Serial No. 40,052, and in Sweden March 3, 1931. Term of patent 14 years.

To all whom it may concern:

Be it known, that I, FREDRIK LJUNGSTROM, a subject of the King of Sweden, residing at Lidingo, Sweden, have invented a new, original, and ornamental Design for Electric Fan, of which the following is a specification, reference being had to the accompanying drawings, forming part thereof:

Fig. 1 is a perspective view of an electric fan showing my new design; and
Fig. 2 is a side view thereof.

I claim:

The ornamental design for an electric fan, as shown.

FREDRIK LJUNGSTROM.
